FISHING REEL

Roy P. Hess, Cleveland Heights, Ohio, assignor to True
Temper Corporation, Cleveland, Ohio

Filed Jan. 4, 1971, Ser. No. 103,957

Term of patent 14 years

Int. Cl. D22—05

U.S. Cl. D22—25

Fig. 1

Fig. 2

Fig. 3

Fig. 4

Fig. 5

Fig. 6

Fig. 7

FIG. 1 is a side elevation of a fishing reel showing my new design;

FIG. 2 is a top plan view thereof;

FIG. 3 is a bottom plan view thereof;

FIG. 4 is a side elevation thereof showing the side opposite FIG. 1;

FIG. 5 is a front elevation thereof;

FIG. 6 is a back elevation thereof; and

FIG. 7 is a section taken along the line 7—7 of FIG. 2.

I claim:

The ornamental design for a fishing reel, as shown.
